FIREPLACE SHIELD

Joseph T. Viggiano, Enterprise, W. Va.

Application March 3, 1948, Serial No. 12,730

2 Claims. (Cl. 126—135)

11

The present invention relates to new and useful improvements in shields for fireplaces to substantially enclose the fireplace when removing ashes therefrom to prevent dust from the ashes from entering the room.

An important object of the invention is to provide a removable fireplace shield which may be easily and quickly set up in position at the fireplace opening and which includes a vertically swingable flap at the front edge of the shield to regulate the draft to a point at the bottom portion of the fireplace to facilitate the starting of a fire therein.

A still further object is to provide a fireplace shield of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the flap in a raised position for use when removing ashes from the fireplace.

Figure 2 is a similar view showing the flap in a lowered position for use when starting a fire;

Figure 3 is a vertical sectional view taken substantially on a line 3—3 of Figure 1;

Figure 4 is a rear perspective view of the shield removed from the fireplace; Figure 5 is an enlarged fragmentary perspective view of the shield.

Figure 6 is an enlarged fragmentary sectional view taken substantially on a line 6-6 of Figure 1 and showing the catch for holding the flap in

Referring now to the drawing in detail wherein for the purpose of illustration I have disclosed a preferred embodiment of the invention the numeral 5 designates the sheet metal shield generally and which includes a forwardly sloping front wall 6 at the upper portion of the shield and substantially triangular shaped end walls 7 at the side edges of the front wall and having their vertical rear edges 8 positioned inwardly at the side edges of a fireplace opening 9, the side walls 7 extending substantially throughout the height of the fireplace as shown in Figure 3 of the drawings.

The upper edge of the front wall 6 is rolled **55** in place, a solid metal comprising a sheet metal sloping front wall and triangular

2

forwardly to form a substantially hook-shaped hanger 10 which engages behind the beading 11 at the lower front edge of the lining 12 for the fireplace to support the shield in a position at 5 the front of the fireplace as shown in Figures 1 and 2 of the drawings.

A vertically swingable flap 13 is hinged at one edge to the lower edge of front wall 6 by a conventional type of hinge structure 14 for swinging downwardly in a rearwardly inclined position at the lower front portion of the shield, the lower edge of the flap being curved upwardly as shown at 15.

15 The flap is held in its raised position against the outer surface of the front wall 6 by means of a combined handle and catch 16 which has one end secured to the front wall 6 by a rivet or the like 17 and extends downwardly from its attached end to provide a downwardly and inwardly curved lower free end 18 which forms a catch under which the free edge of the flap 13 is snapped to hold the flap in its raised position.

is snapped to hold the flap in its raised position.

In the operation of the device when it is desired to remove ashes from the fireplace or from a coal grate 19 therein the flap 13 is held in its raised position and the shield placed in the fireplace as shown in Figures 1 and 2 of the drawings. The forwardly projecting upper portion of the shield prevents dust from the ashes from entering the room, the lower front portion of the shield being of sufficient height to enable an ash can or receptacle 20 to be placed thereunder adjacent the grate 19.

When starting a fire in the fireplace the flap 13 is lowered into a position as shown in Figure 2, the lower curved edge 15 of the flap providing a draft opening 21 at the extreme lower portion of the fireplace to more effectively aid the starting of the fire.

40 In view of the foregoing description taken in conjunction with the accompanying drawings it is believed that a clear understanding of the device will be quite apparent to those skilled in this art. A more detailed description is accordingly
45 deemed unnecessary.

40 deemed unnecessary.
It is to be understood, however, that even though there is herein shown and described a preferred embodiment of the invention the same is susceptible to certain changes fully comprehended by the spirit of the invention as herein 50 described and the scope of the appended claims.

Having described the invention, what is claimed as new is:

side walls fitting in the opening of the fireplace from top to bottom of said opening, a hanger at the upper edge of the front wall securing the shield in the fireplace opening with the front wall projecting forwardly and downwardly therefrom and having its lower edge positioned above the hearth of the fireplace to afford access thereto for removing ashes therefrom, and a vertically swingable flap at the lower edge of the front wall swingable thereon into a rearwardly and downwardly inclined position against said side walls to close said shield below said front wall.

2. A fireplace, a shield therefor comprising a sheet metal sloping front wall and triangular side walls fitting in the opening of the fireplace from top to bottom of said opening, a hanger at the upper edge of the front wall securing the shield in the fireplace opening with the front wall projecting forwardly and downwardly therefrom and having its lower edge positioned above the hearth of the fireplace to afford access thereto for removing ashes therefrom, and a vertically swingable flap at the lower edge of the front wall swingable thereon into a rearwardly

and downwardly inclined position against said side walls to close the shield below said front wall, said flap having a curved lower edge forming a draft opening at the bottom of the fireplace opening underneath said wall.

JOSEPH T. VIGGIANO.
